UNITED STATES PATENT OFFICE.

HOWARD S. GARDNER, OF EAST ORANGE, NEW JERSEY.

HOPPER AND THE LIKE.

1,359,161.

Specification of Letters Patent. Patented Nov. 16, 1920.

Application filed June 7, 1917. Serial No. 173,285.

To all whom it may concern:

Be it known that I, HOWARD S. GARDNER, a citizen of the United States, and resident of East Orange, county of Essex, State of New Jersey, have made certain new and useful Improvements in Hoppers and the like, of which the following is a specification.

My invention relates to hoppers and the like and more particularly to that type thereof commonly known as receiving hoppers and has for its object to improve and simplify the construction thereof. My invention further contemplates an improved operating mechanism for the gate or door whereby the latter may be moved to an open position, with a minimum of effort and whereby any resistance to this movement interposed by the load is readily and efficiently overcome. A further purpose of my invention is to provide an improved exit construction in which the possibility of the material becoming set or bound in said exit is reduced to a minimum. My invention will be fully described hereinafter and the features of novelty will be pointed out in the appended claims.

In the accompanying drawings which illustrate an example of my invention Figure 1 is a front view of my improved hopper; Fig. 2 is a central vertical section thereof; Fig. 3 is a detail front view, the gate or door being omitted; Fig. 4 is a detail side view; Fig. 5 is a plan view; Fig. 6 is a detail side view on an enlarged scale; and Fig. 7 is a detail section on the line 7—7 of Fig. 6.

As shown in the drawings the hopper comprises the usual receptacle 10 constructed of any suitable material and having any desirable shape and dimensions. The receptacle 10 is provided with downwardly inclined and converging walls 11 and with an inclined exit chute 12 which forms a continuation of said walls. The discharge end 45 of the chute 12 is controlled and normally closed by means of a gate or door 13 carried by side members 14 which extend along the opposite outer walls of chute 12. Each side member 14 is formed with an opening 15 for the accommodation of an eccentric 16 and is further provided with a block 17 secured in position by means of rivets or other fastening means 18. The blocks 17 serve to increase the strength and rigidity of the 50 structure and are each provided with an opening 19, also for the accommodation of

the eccentric 16, the openings 19 each being in registry with an opening 15. The eccentrics 16 are rotatably and eccentrically mounted upon studs 20 projecting outwardly 60 from blocks 21, the latter being fastened to the outer side walls of the chute 12 in any suitable manner by means of rivets 22. In their outer faces the eccentrics 16 are preferably provided with diametrically extending recesses into which levers 23 are fitted and secured to the eccentrics by means of fastening devices 24. These levers 23 project radially beyond the eccentrics and extend beyond the door or gate 13 and near 70 their free ends are connected by means of a cross-bar 25, a similar cross-bar 26 extending between said levers 23 in proximity to the door or gate 13. The cross-bars 25 and 26 are so dimensioned and arranged with respect to each other and to said levers 23 that the inner ends of the latter exert an inward force toward each other whereby the eccentrics 16 are maintained against any appreciable axial displacement relatively to 80 the studs 20. In other words the cross-bar 26 is slightly shorter than the bar 25 so that the levers 23 are drawn inwardly toward each other when the parts are operatively combined. The preferred arrangement includes arms 27 secured to the side members 14 and also projecting beyond the gate or door 13, members 28 being pivotally connected at 29 with said arms at their free 85 ends. Flexible connections 30, such as 90 ropes, cables, or the like are connected at one end with said members 28 and pass through and over pulleys 31 suspended from the receptacle 10 at proper points. Counterbalance weights 32 are connected with the free 95 ends of said connections 30 so as to be suspended thereby and serve to counterbalance the weight of the door or gate 13 when the latter is opened to discharge material from the hopper. In order to lock the eccentrics 16 or their equivalents against unintentional 100 operation any suitable means may be provided; for instance as shown in the drawings, I may provide a dog or catch 33 pivotally mounted on the cross-bar 26 and adapted in its normal position to extend beneath the gate or door 13 and thus secure the levers 23 against movement, relatively to said gate or door. In this way the eccentrics 16 are locked against unintentional operation from 105 any cause as for instance the pressure of the load against the door or gate 13. The dog 110

or catch 33 may be maintained in and returned to its normal position by gravity or in any suitable and equivalent manner and is preferably provided with a handle 34 whereby the catch may be moved to a position in which the lever 23 and consequently the eccentrics 16 are released when an intentional opening of the door or gate is desired.

10 Hoppers of the kind to which my improvement relates are often used as temporary receptacles for concrete and other coalescent material which has a tendency to set and to become clogged particularly in the exit chute and thus prevent or at least retard the discharge of the contents of the hopper. In order to reduce this tendency to a minimum and in some cases to prevent it, I provide the chute 12 with interior walls 15 or wings 35 which follow the downward inclination of said chute and which converge toward the free end thereof. With this arrangement, as shown in Fig. 3, the discharge opening is reduced and the walls or wings of the chute converge toward the same, so that there is nothing which will cause binding of the material or clogging of the chute.

20 As before stated coalescent material after being introduced into the hopper has a tendency to set, even if permitted to remain at rest only a short time; as this setting takes place its effects are communicated to the door or gate 13 which as a result is oftentimes firmly held in a closed position and even under the most favorable conditions can be opened only with extreme difficulty. These objections are overcome in my improvement which operates as follows:

25 When it is intended to discharge the contents of the receptacle 10, in part or completely, the handle 34 is first moved to swing the dog 33 to a position in which the levers 23 and consequently the eccentrics 16 are released. The levers 23 are then moved in the arc of a circle through the medium of the cross-bar 25 which brings about a rotation of the eccentrics 16 upon the studs 20. As this occurs the eccentrics 16 exert

30 a force or push upon the blocks 17 and side members 14 tending to move the gate or door 13 in a linear direction away from the end of the chute 12. In this way the door or gate 13 is released from the contents and

35 freed from any resistance exerted thereby and by manual force exerted in an upward direction assisted by the weights 32 is easily swung in the arc of a circle to an open position. The arrangement of the eccentrics 16 and levers 23 is such that a tremendous leverage is exerted upon the side members 14 and blocks 17 with only a comparatively slight effort on the part of the operator.

40 Thus any resistance to the opening of the door which may be offered by the contents

of the hopper is quickly and easily overcome and the door or gate is first moved away from the mouth of the chute after which it is easily moved to an open position. After the door or gate 13 has reached its 70 open position the levers 23, upon being relieved from the manual force exerted in opening the door or gate, are permitted to drop back to their initial position relatively to the door, the dog 33 snapping beneath 75 the lower edge thereof. As the levers 23 move in the return direction the gate or door 13 is drawn back through the medium of the eccentrics 16 and is thus in position to move directly in front of the chute 12 80 to close the same in the intended manner. With this arrangement, when the door has been returned to its closed position, the eccentrics 16 are again locked until again released as hereinbefore described.

85 The gate is returned to its closed position in any suitable manner and is moved back into engagement with the end of the chute 12 by actuating the levers 23 in the reverse direction as will be readily apparent.

90 It will, of course, be apparent that the counterweights whereby the weight of said gate or door is balanced may be replaced by any other means whereby the same result is obtained or in some cases omitted 95 entirely.

99 Various changes in the specific construction shown and described may be made within the scope of the claims without departing from the spirit of my invention. 100

I claim:

1. A hopper or the like having a discharge opening, a pivotally movable gate controlling said discharge opening, eccentrics rotatably mounted on said hopper and 105 constituting the pivots on which said gate swings and means for actuating said eccentrics to linearly move said gate away from said discharge opening prior to its pivotal movement to an open position. 110

2. A hopper or the like having a discharge opening, a pivotally movable gate controlling said discharge opening, eccentrics rotatably mounted on said hopper and constituting the pivots on which said gate 115 swings, levers connected with said eccentrics whereby the latter are actuated to linearly move said gate away from said discharge opening prior to its pivotal movement to an open position and a cross-bar connecting 120 said levers whereby the latter are operated.

3. A hopper or the like having a discharge chute, eccentrics rotatably mounted on opposite side walls of said chute, side members pivotally mounted on said eccentrics, a gate carried by said side members and controlling the open end of said chute and levers connected with said eccentrics to rotate same whereby said side members are 125 linearly actuated to move said gate away 130

from the end of said chute before it begins a pivotal opening movement.

4. A hopper or the like having a discharge chute, eccentrics rotatably mounted on opposite side walls of said chute, side members pivotally mounted on said eccentrics, a gate carried by said side members and controlling the open end of said chute, connected levers secured to said eccentrics to rotate same whereby said side members are linearly actuated to move said gate away from the end of said chute and a counter-balance weight whereby said gate is pivotally moved to an open position after it has been moved away from said end of the chute.

5. A hopper or the like having a discharge chute, eccentrics rotatably mounted on opposite side walls of said chute, side members pivotally mounted on said eccen-
trics, a gate carried by said side members

and controlling the open end of said chute, connected levers secured to said eccentrics to rotate same whereby said side members are linearly actuated to move said gate away from the end of said chute and a pivoted 25 dog whereby said gate is locked in its normal position.

6. The combination of a hopper (or the like) having converging walls, a downwardly inclined exit chute forming a continuation of said converging walls, upright wings located within said chute and distinct from the walls thereof, said wings converging toward the discharge end of such chute and terminating thereat and means for controlling said discharge opening.

In testimony whereof I have hereunto set my hand.

HOWARD S. GARDNER.
